UNITED STATES PATENT OFFICE.

EDWARD E. CLAUSSEN, OF HARTFORD, CONNECTICUT.

MACHINE FOR FORMING PLASTIC ARTICLES.

1,359,489.

Specification of Letters Patent. Patented Nov. 23, 1920.

Application filed September 14, 1918. Serial No. 254,044.

To all whom it may concern:

Be it known that I, EDWARD E. CLAUSSEN, a citizen of the United States, residing at Hartford, in the county of Hartford and 5 State of Connecticut, have invented certain new and useful Improvements in Machines for Forming Plastic Articles, of which the following is a specification.

This invention relates to a machine for 10 forming plastic articles. A machine involving the invention can be used with advantage in a number of different fields. The primary motive I have in view is the provision of a machine of the kind set forth by 15 which I can in a rapid and accurate manner produce a plastic article. As will be inferred, the plastic substance which is brought under the action of the machine, may be of any desirable material and the article produced by the machine may likewise 20 be used in various ways. I obtain excellent results however, by the use of paper pulp which is therefore preferred. It should also be noted that while the article produced by 25 the machine is desirably hollow, this may not always be necessary. The article made from paper pulp may be used in a large number of connections. As an illustration it may be utilized as a tube or it may constitute the body of a receptacle or container 30 or any other part or all of such a receptacle. Likewise the shape of the body may vary. It may be for instance cylindrical and plain 35 interiorly and exteriorly or it may be fluted or corrugated on one of its sides. On the other hand it may be rectangular or some other convenient shape in cross section.

In the drawings I show in detail a few of 40 the several forms of embodiment of the invention which to enable those skilled in the art to practice the invention, will be set forth fully in the following description. As will be understood, I am in no sense restricted to this particular disclosure; I may 45 depart therefrom in several particulars within the scope of the invention, defined by the claims following said description.

Referring to said drawings:

Figure 1 is an elevation of the machine.

50 Fig. 2 is a central vertical sectional view on line 2—2 of Fig. 3 looking in the direction of the arrows.

Fig. 3 is a top plan view of the machine.

55 Fig. 4 is a horizontal section on the line 4—4 of Fig. 1 looking in the direction of

the arrows the casing however being omitted.

Fig. 5 is a horizontal section on the line 5—5 of Fig. 2.

Fig. 6 is a vertical section of the upper 60 portion of the pressing mechanism.

Fig. 7 is a cross section on the line 7—7 of Fig. 5 looking in the direction of the arrows.

Figs. 8 and 9 are horizontal sectional 65 detail views of modified constructions.

Like characters refer to like parts throughout the several views.

The different parts of the machine may be carried upon any suitable framework. 70 That shown for the purpose comprises a table as 2, provided with several depending legs 3, of which there may be any number, generally four, at the corners of the table which is practically rectangular in form. 75 Upon the top of the table 2 rests a casing or housing 4, usually cruciform in plan as is the table. This casing or housing serves as an inclosure for several of the parts hereinafter described. The top 5 of the table is 80 practically horizontal, being situated a short distance below the marginal portion upon which the housing or casing rests and is generally suitably rigidly secured. The table has in addition a bottom 6. 85

In the production of a hollow article, such for instance as a tube, it is desirable if not necessary, to provide a core or mandrel upon or around which the plastic substance is molded. The core or mandrel may vary 90 as to shape and there may in fact, be instances where its use is not necessary. That shown in the form of machine illustrated by Figs. 1 to 7 and Fig. 8 is practically cylindrical. That shown in Fig. 9 is rectangular. 95 I will of course first describe the core or mandrel used in connection with the form of machine illustrated by Figs. 1 to 7 inclusive. In this the core or mandrel is designated by 7. It extends through an 100 opening in the top 5 and the bottom 6 of the table; the bottom having a flange or tubular extension 8 surrounding the lower portion of the core or mandrel. The latter extends a short distance below the flange 8 105 and is preferably given a proper movement, for instance in a rotary manner to prevent in the present instance, its sticking to the plastic or pulp mass surrounding it. It is not always necessary to impart such a 110

- movement to the core or mandrel as where it is rectangular it is not given such rotary movement; in fact it might be otherwise operated to prevent the condition to which I have alluded. Said core or mandrel has an external flange or collar 9, resting upon the upper surface of the bottom 6. As shown the lower end of the core or mandrel projects a short distance below the flange or tubular extension 8 and its upper portion extends short of the upper edge of the casing or housing 4, as shown best for illustration in Fig. 2.
- Said core or mandrel may be operated rotatively in any convenient manner. The means represented for the purpose will now be set forth. As shown (Figs. 1 and 2) said mandrel has fastened to its lower end the worm gear 10, in mesh with the worm 11 at the inner end of the shaft 12, said shaft 12 being sustained for example, by a bearing 13 upon the table 2 and turned in some suitable way as by a pulley 14, fastened to the outer end of said shaft, the driving belt of the pulley being not shown. It will be clearly evident that upon the rotation of the pulley 14, the mandrel or core, through the intermediate parts, will be rotated.
- Said core or mandrel as shown, also serves as a means for the conduct of a suitable coating substance to the interior of the tubular article being formed. Obviously this coating substance may vary nor is it essential that it be conveyed to its place of application through the core or mandrel. I have found paraffin a suitable material for coating the interior of the tube and it is conveyed in a liquid condition to its place of application. In this particular use it is desirable also to use a heater or burner, such as a gas heater, to prevent the paraffin, when it is being used, from solidifying. The gas for the heater may be conveyed to the place of use in any convenient manner, desirably also through the core or mandrel. What is of importance is the fact that the paraffin lubricates the interior of the tubular pulp body and prevents effectually the pulp sticking to the core.
- The machine, preferably, comprises molding or forming mechanism made up of a plurality of molding or forming members of which there may be any desirable number and the construction of which may vary, although they are generally of annular form, such for instance but not essentially circular in shape. These molding or forming members cooperate to present practically the external form of the article being made. They may be peripherally grooved, plain, corrugated or of other shape. They are practically in the form of wheels, being made to turn in a rotary direction and functioning after the fashion of what are known as "cages" in this art or in the art of producing objects from pulp masses. There are four of such molding or forming members or cages, respectively, 15, 16, 17 and 18. These molding or forming members in the present instance, rotate about axes in the same or practically the same horizontal plane, and their peripheries mate to present a continuous structure which is circular. Each molding or forming member 75 comprises a hub or body as 19. The hub or body of the forming or molding member 15 is fastened to the shaft 20, (Fig. 4) the body of the molding or forming member 16 being fastened to the shaft 21 at right angles 80 to the shaft 20, the hub or body of the molding member 17 being fastened to the shaft 22, parallel with the shaft 20 and as a consequence, at right angles to the shaft 21, the body of the molding member 18 being 85 fastened to the shaft 23. The shafts 20 and 21 are connected by bevel gears 24 at their ends, the ends of the shafts 21 and 22 being connected by bevel gears 25, while bevel gears 26 connect the shafts 22 and 23. 90 It should be noted that the diameters of the annular or circular molding or forming members are as shown, practically the same. To the shaft 20 at the outer end thereof is fastened the spur gear 27, in mesh with the 95 spur gear 28, fastened to the counter shaft 29 (Fig. 2) on the frame of the machine, the gear 28 being in mesh with a pinion 30 on the shaft 32, supported by the frame of the machine. To this shaft 32, is fastened 100 a driver as the pulley 33. When this pulley is rotated it will be clear that through the agency of the intermediate parts, the four molding or forming members, 15, 16, 17 and 18 will simultaneously rotate. In Fig. 2 105 in fact, I indicate by arrows the direction of rotation of the driver or pulley 33.
- The hubs 19 of the respective molding members as shown best in Fig. 4, are somewhat elongated and at one end of each is 110 the web 34 of the particular molding or forming member. The peripheries of these webs are beveled, the beveled surface of the respective webs being in contact. From the webs laterally extend the ribs 35, each series 115 being united by an annular portion as 36 and each annular portion 36 as will be understood, being parallel with its web. The annular portions 36 are beveled oppositely to the beveled peripheries of the respective webs, the ribs 35 as will be understood being connected with the respective webs 34 and portions 36. The peripheries of the several forming members consist as shown, of the foraminous or reticulated portions 37, which are transversely arched, the convexed sides of the respective foraminous portions 37 lying in and being held against arched seats 38 of the respective sets of ribs 35. These foraminous portions 37 constitute 125 130

the effective portions of the molding or forming members which as will be clear, are hollow or practically so. When the lateral parts of the peripheries of the four molding members engage as shown, for instance, in Fig. 4 the foraminous portions 37, collectively present an opening which is shown as being circular although this may not always be necessary. The circular formation is 10 illustrated however in Fig. 3 of the core or mandrel 7. It will be seen upon examining the last view that the ribs 35 are practically triangular in cross sections with their knife edges facing outward and their flattened bases inward. The foraminous portions extend from side to side of the respective molding members and through them is drawn the excess water in the pulp.

In connection with the several forming or 20 molding members, 15, 16, 17, 18, there is provided suction means which may, like the other parts vary as to character although suction boxes as 39 and 40 (Fig. 2) answer in this particular. These suction boxes (see 25 also Fig. 4) are of practically angular form, each having two branches. The suction boxes are hollow, being open on their sides next the peripheries of the molding members and closed on their opposite sides. At 30 their elbows or angles, said suction boxes 39 and 40 have tubular outlets as 41 (Fig. 7) connected as will appear at their lower ends with suitable exhaust means. The branches of each suction box, extend into the respective forming or molding members and their closed ends bear against the webs 34 of said forming or molding members as shown for instance, in Fig. 4. The open sides of the 35 suction boxes fit against the respective ribs 35, the branches of the suction boxes being curved to conform practically to the peripheral portions of the molding or forming members. The branches of the several suction boxes have around the closed sides, 40 bosses as 42 which receive springs as 43^a, bearing against the respective hubs 19 as shown in both Fig. 2 and Fig. 4. The springs permit a certain amount of movement of the suction boxes 39 and 40, under 45 varying conditions, and at the same time hold the open ends of said boxes, properly against the ribs 35 of the several molding members.

The top 2 has within it (Figs. 2 and 5) 50 the duct or passage 43 with which is connected a pipe 44 for the supplying of the pulp mass. The head or inner end of this duct or passage 43 is of practically circular shape. As shown best in Fig. 5, said head 55 partially surrounds and is concentric with the core or mandrel 7. There is in radial line with the supply passage 43, the discharge passage 46 having at its inner end the branches 47 at opposite sides of the head 60 end of the passage or duct 43. It will be

clear of course that the passage or duct 43 is not in direct communication with the passage or duct 46. With the latter is connected the pipe 48 intended for the discharge of water. The pipes or tubular extensions 41 to which I have referred and which receive the excess water drawn from the pulp mass, are connected at their lower ends by universal joints 49 with the top 5 and empty directly into the passage 47 as 70 represented by Fig. 4 and Fig. 7. The tubes 41 are provided at the lower ends with flanges 51 which receive screws 52 surrounded by springs 53 bearing against heads of said screws and also against the flange 80 51 thus maintaining the tubes or pipes 41 in water-tight connection with the top 5.

The lower portion of the core or mandrel 7 is surrounded by the jacket or sleeve 54, spaced therefrom, the space between the 85 jacket or sleeve 54 and the mandrel being for the passage of the pulp mass. This space it might be noted at this time, is greater according to the thickness of the tube to be formed. The upper edge of this 90 jacket or sleeve fits against the peripheries of the several molding members 15, 16, 17 and 18, being beveled to secure proper contact therewith. The jacket or sleeve 54 has a circumferential annular flange 55 against 95 which bears the upper end of the spring 56, engaging at its lower end the stuffing box 57 which surrounds the jacket or sleeve 54 near the lower end thereof. Said stuffing box surrounds said mandrel and fits an 100 opening in the top 5 of the table as best shown in Fig. 2. This jacket or sleeve 54 extends downward into the head end of the duct or passage 43 and is concentric with said head end as shown in Fig. 5. It will be 105 clear that upon the application of suction to the pipe 48, the suction being in the direction of the arrow on the right in Fig. 2 and upon introduction of a pulp mass into the pipe 44, this pulp mass will be drawn into 110 the duct or passage 43 and then into the space between the jacket 54 and the mandrel 7 being deposited on the peripheries of the 115 molding members 15, 16, 17 and 18. The several molding members jointly form the pulp mass into a tube and give to it an initial pressure not necessarily intense or extreme. As the several forming or molding members rotate they feed the tubular mass of pulp upward where the same is further and finely compressed and the water removed from it. At this second stage of the operation paraffin is applied to the interior of the tubular body being produced and said tubular body is cut into suitable 125 lengths in some desirable manner. It may not always be necessary to coat the plastic or paper pulp body although it is desirable to do so.

There are four of these compressing mem- 130

bers arranged above the molding or forming members, 15, 16, 17 and 18 and they are denoted respectively in a general way by 63, 64, 65 and 66. Each comprises a central hub 67 fastened respectively to shafts 32, 69, 70 and 71 (Fig. 3) the shafts 32 and 70 being parallel with each other while the shafts 69 and 71 are also parallel. Said shafts 32, 69, 70 and 71 are geared to each other by bevel gears 68. These several compressing members 63, 64, 65 and 66 are of practically circular form virtually being not unlike said molding members or cages.

Each of the hollow compression members 15 in addition to the hub 67 to which I have referred, comprises a circular and perforated periphery or rim 71' and they receive the branches of the vacuum boxes 74. These vacuum boxes 74 have already been described, that is to say each is angular, one branch of each being located in the hollow body of a pressure member and the other branch being located in the hollow body of an adjacent pressure member. The vacuum boxes 25 are held yieldingly advanced by springs 75, mounting and operating like the springs 42 already described, the springs acting to hold the open sides of the vacuum boxes against the inner circular sides of the peripheries of the respective compression members. The lateral positions of these compression members are beveled where they come in contact and their peripheries present jointly a circular opening through which the pulp mass is advanced, the said pulp mass being further advanced or fed forward by said pressure members. The pressure members feed or advance the pulp upwardly in the present case and at the same time extract any moisture that may be in the pulp, the moisture or water entering the vacuum boxes 74. These vacuum boxes 74 have at their elbows downwardly extending ducts 75' which open at their lower ends 40 into the branches 47 of the discharge passage 46. Said pressure members are provided with peripheral blades 76 which mate and coöperate to cut through the plastic tube being advanced and thus cut it into suitable lengths, the lengths which are cut, being as a matter of convenience, denoted by 76' in each case. The manner of disposing of them may vary although a means which is advantageous and answers the purpose will be hereinafter set forth.

The core or mandrel 7 contains a supply tube 77 (Figs. 2 and 6) the upper end of which is enlarged to agree in external form with the mandrel or core 7. Into this enlarged upper end is threaded the pendent boss of the head 78, the lower end of said tube 77 being furnished with a stuffing box 79. Connected with the lower end of said tube 77 is a pipe 80 which constitutes a convenient means for the supply of paraffin

or its equivalent to the tube or pipe 77 which flows upward and out of the passages 81 formed angularly in the intermediate portion of the head 78, the streams of paraffin issuing from said openings 81 being directed upon the interior of the tubular structure during its formation. Extending through tube or pipe 77 is a pipe as 82 for the supply of ordinary combustible gas. This pipe 82 has at its upper end a burner 75 83 in the chamber 84 of the head 78. The gas issuing from this burner 83 may be ignited thereat and heats the head 78 sufficiently to prevent the paraffin solidifying at its place of application.

The lengths 76' of the stock are received between the jaws of a gripper as 85, supported by the sleeve 86 (Figs. 2 and 3) fitted around the rod 87 extending from the bracket 88, rigid with the housing 4. The movable jaw of the gripper is operated by the band 88', slideable on the sleeve 86. This band 88' has loosely connected with it, the rod 90, operable by the cam 91 on the shaft 70. After a section as 76' is cut, the sleeve 90 86 is turned. Before being turned however, it is slightly raised through the action of the cam 97 on the rod 98 which has a connection with said sleeve 86. The turning is done after the sleeve is elevated by the stud 99, which enters the groove of a cam 100, rigid with said sleeve. Each length or blank is swung over onto the belt 101.

In Fig. 8 I show four forming devices denoted in a general way by 105. They are like forming devices heretofore described except that their peripheries instead of being concave are corrugated as at 106. This produces a tube which is externally corrugated. The core or mandrel used in this 105 corrugated tube is denoted by 107 and is circular or cylindrical. In Fig. 9 I show four forming members as 108 whose peripheries are plain. The consequence is that in this event the tube produced is rectangular 110 in cross section. The core 109 is also rectangular in cross section.

The casing 4 has a pipe 110 for the water which enters the casing.

What I claim is:

115

1. A machine of the class described comprising molding means, a core, means for securing the supply of a moldable substance to the core, the molding means shaping the substance on the core and being movable to effect the feeding of the formed article along the core.

120

2. A machine of the class described comprising a plurality of molding members, a core surrounded by the molding members, means for containing a moldable substance, the molding members coöperating to form the substance into a predetermined shape on the core, and means in the molding members for causing the supply of the substance to 125 130

the place where it is to be operated upon by the molding members.

3. A machine of the class described comprising a plurality of hollow, peripherally 5 foraminous molding members, a core surrounded by the molding members, means for containing a moldable substance, the molding members coöperating to form the substance into a predetermined shape on the 10 core, and means within the molding members for causing the supply of the substance to the place where it is to be acted upon by said molding members.

4. A machine of the class described comprising a plurality of molding members, 15 means for containing a moldable substance, a core surrounded by the molding members, the molding members coöperating to form the substance into a predetermined shape on 20 the core and their active portions being foraminous, and means acting through the foraminous portions to cause the supply of the substance to the place where it is to be acted upon by said members.

25 5. A machine of the class described, comprising a plurality of hollow molding members, the active portions of which are foraminous, means for containing a moldable substance, a core surrounded by the molded 30 members, the molding members coöperating to form the substance into a predetermined shape on the core, and means acting through the foraminous portions to draw the said substance to the place where it is to be acted 35 upon by said molding members.

40 6. A machine of the class described comprising several annular, rotary molding members disposed with respect to each other to present a circular opening, a core surrounded by the molding members, the active portions of said molding members being foraminous, a source of supply of a plastic substance, and means for causing the substance to pass through said circular opening 45 where the active portions of the molding members act on the substance to mold the same on the core.

50 7. A machine of the class described comprising several annular, rotary molding members disposed with respect to each other to present an opening, the active portions of said molding members being foraminous, a core surrounded by the molding members, a source of supply of a plastic substance, 55 and means for causing the plastic substance to pass through said opening where the active portions of the molding members act on the substance to mold the same on the core.

60 8. A machine of the class described comprising several movable molding members disposed with respect to each other to form an opening, the active portions of the members being foraminous, a core extending through said opening, a source of supply of 65 plastic substance, and means for causing

the plastic substance to pass through said opening where the active portions of the molding members act on the substance to mold the same on the core.

9. A machine of the class described comprising several movable molding members disposed with respect to each other to form an opening, the active portions of the members being foraminous, a core extending through said opening, a source of supply 70 of plastic substance, and means within the members, for causing the plastic substance to pass through said opening where the active portions of the molding members can act on the substance to mold the same on the core. 75

10. A machine of the class described comprising a core, a source of plastic substance, means for forming the plastic substance around the core, means for conducting a coating substance to the interior of the article 80 formed on the core, and means for imparting a movement to said core.

11. A machine of the class described comprising a core, a source of plastic substance, 85 means for forming the plastic substance around the core, means for conducting a coating substance to the interior of the article formed on the core, and means for applying heat approximately at the place of application of the coating substance. 95

12. A machine of the class described comprising a plurality of molding members disposed respectively in edgewise relation to each other to present an opening, the active portions of said molding members being 100 foraminous, a core extending through said opening and being spaced from the peripheries of the molding members, and means for drawing a moldable substance through said space where it can adhere to the core 105 to be acted while thereupon by the molding members.

13. A machine of the class described comprising a plurality of molding members disposed respectively in edgewise relation to 110 each other to present an opening, the active portions of said molding members being foraminous, a core extending through said opening and spaced from the peripheries of the molding members, means for drawing 115 a moldable substance through said space where it can adhere to the core to be acted upon while thereon by the molding members, and means surrounding the core to act on the stock on the core to compress the same 120 after it is acted upon by the molding members.

14. A machine of the class described comprising a plurality of molding members disposed respectively in edgewise relation to 125 each other to present an opening, the active portions of said molding members being foraminous, a core extending through said opening and spaced from the peripheries of the molding members, means for drawing a 130

5 moldable substance through said space where it can adhere to the core to be acted upon while thereon by the molding members, and a series of molding members disposed in edgewise relation to each other and in which the core is mounted, said latter members acting on the stock on the core to compress the same.

10 15. A machine of the class described comprising a receptacle to contain a plastic substance, a tubular element in communication with the receptacle, a core extending through the tubular element, a plurality of hollow tubular molding members disposed in edge-
15 wise relation to each other to present an opening through which the core extends, the active portions of said molding members being foraminous, the molding members acting on the substance on the core.

20 25. 16. A machine of the class described comprising a plurality of molding members, a core surrounded by the molding members, means for containing a moldable substance, the molding members coöperating to form the substance into a predetermined shape

30 on the core, means in the molding members for causing the supply of the substance to the place where it is to be operated upon by the molding members, and means for withdrawing moisture from the moldable sub-
stance.

35 17. A machine of the class described comprising a plurality of molding members, a core surrounded by the molding members, means for containing a moldable substance, the molding members coöperating to form the substance into a predetermined shape on the core, means in the molding members for causing the supply of the substance to the place where it is to be operated upon by the molding members, and suction boxes in communication with the molding members, for withdrawing moisture from the moldable substance.

40 45 In testimony whereof I affix my signature in the presence of two witnesses.

EDWARD E. CLAUSSEN.
